UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A MISS'S WALKING-SKIRT.

SPECIFICATION forming part of Design No. 14,514, dated December 25, 1883.

Application filed October 27, 1883. Term of patent 3½ years.

To all whom it may concern:

Be it known that I, LOUISE TULLY, of the city, county, and State of New York, have invented and produced a new and original Design for a Pattern of a Miss's Walking-Skirt, (numbered 8,933;) and I do hereby declare that the engraved prints accompanying this specification convey to anyone accustomed to using paper patterns a clear understanding of how a garment made up by the pattern will appear.

The design displays a short walking-skirt, a deep narrow panel at the left side; a drapery which slightly overlaps the front of the panel extends across the right side, falls in a deep

point at its left side edge, and shows plaits in its upper and right side edges, and a back drapery that falls straight at the right side, and is draped to fall in a point by a cluster of plaits under a deep plait at the left side.

What I claim as my invention, and desire to secure by Letters Patent, is—

The design for a miss's walking-skirt, as shown in the engraved prints accompanying this specification.

LOUISE TULLY.
